UNITED STATES PATENT OFFICE.

WILLIAM WALLACE DICKINSON, JR., OF LITTLE ROCK, ARKANSAS, ASSIGNOR TO THE AMERICAN EQUIPMENT COMPANY, OF CHICAGO, ILLINOIS, A CORPORATION OF OHIO.

APPARATUS FOR HANDLING AND TRANSPORTING BRICK AND THE LIKE.

Application filed March 20, 1918. Serial No. 223,555.

To all whom it may concern:

Be it known that WILLIAM WALLACE DICKINSON, Jr., citizen of the United States, residing at Little Rock, in the county of 5 Pulaski and State of Arkansas, have invented a certain new and useful Improvement in Apparatus for Handling and Transporting Brick and the like, of which the following is a full, clear, and exact description, reference being had to the accompanying drawings.

This invention relates to the manufacture of brick and has for its general object to improve the methods and appliances for 15 handling the bricks at any time between their delivery by the brick machine and the time when they are set upon the conveyance whereby they are transported to the user. More particularly the object of this invention 20 concerns the provision of a device whereby unburned bricks can be collected together and set upon the kiln in predetermined spaced relation although numerous other objects and advantages are present.

25 This invention relates particularly to the making of common brick in which the value of the product is comparatively small, the output necessarily large, and the largest single expense is that of labor. Heretofore 30 the bricks delivered from a brick machine, either of the soft-mud or stiff-mud type, have ordinarily been placed by hand upon suitable pallets or drying cars (depending upon the solidity and stiffness of the bricks)

35 then transported either to a drying house, drying shed, or kiln shed, and finally set by hand upon the kiln, either directly or after various intermediate handlings with wheelbarrows. This procedure has been modified 40 only by the peculiar characteristics of different clays; for some clays can be pressed into bricks of such stiffness as to permit their immediate building into burning kilns, provided that not too many courses be laid

45 in one day; other clays, while stiff enough to bear the weight of two or three courses on a pallet, have to be inserted in a drying oven for a few days before placing upon the kiln; some clays, while they might be sufficiently stiff immediately upon pressing to set into a kiln, are necessarily dried for a time before burning in order to prevent their becoming warped, bulged, and broken by the heat; and others have to be inserted in single

layers into drying ovens, or laid on racks in the open air for a time before they can be handled at all. In all cases, however, a great deal of manual handling has been necessary, while drying cars, handling apparatus, and the like devices, in the few instances where 50 they have been used, have been extremely expensive, and generally complicated and unreliable.

The objects of the present invention are the provision of a means and method for 55 receiving the bricks directly from a conveying mechanism such as a conveying belt, and setting the same mechanically in their final position upon the kiln or other device, together with all intermediate steps which 60 may be necessary, without the necessity of touching the hand thereto; the provision of a new and improved type and construction 65 of pallet for receiving, for drying, for delivering the unburned brick; the provision 70 of a new and improved means and method for delivering the bricks to the pallet; the provision of new and improved expedients 75 for discharging the pallets; the provision 80 of new and improved means for setting the brick on the kiln in separated relation; the provision of new and improved means for 85 placing the bricks upon the pallets; the provision of new and improved means for transporting and handling the pallets; 90 while further objects and advantages of my 95 said invention will become apparent as the description proceeds.

In the drawings accompanying and forming a part of this application I have shown 90 one of the many operative forms in which my invention may be embodied; and while the present application will illustrate and describe the preferred construction of the 95 pallet and its adjuncts, together with means of loading and discharging the same and my improved method of building a kiln therefrom, the claims will be confined more specifically to the means for loading and transporting said pallet, reserving the other matters for a subsequent application or applications. In these drawings Fig. 1 is a diagrammatic view of my improved system; Fig. 2 is a diagrammatic view showing the 100 method of discharging the bricks from the pallet; Fig. 3 is a cross-sectional view of the conveyor illustrated in Fig. 1 showing a pallet thereon; Fig. 4 is a sectional view 105

on the line 4—4 of Figs. 5 and 6 showing the method of loading the bricks; Fig. 5 represents a side elevation and Fig. 6 a top plan view of the parts illustrated in Fig. 4; Fig. 7 is a detail view showing the construction and mode of loading the pallet; Fig. 8 is a top plan view of a portion of the pallet showing the preferred arrangement of bricks thereon; Fig. 9 is a sectional view on the line 9—9 of Fig. 10, and Fig. 10 a similar view on the line 10—10 of Fig. 9, illustrating the construction of the control-box shown in Fig. 4; Figs. 11 and 12 represent cross-sectional views upon the lines 11—11 and 12—12 respectively of Fig. 5; Fig. 13 illustrates a modified arrangement for transporting and inclining the pallets; and Fig. 14 is a bottom plan view of one end of the car shown in Fig. 13.

20 Describing the drawings with regard to the reference characters thereon A represents a conveying belt, B a dry house and C a kiln-shed or kiln-yard. D represents a traveling conveyor system, of any convenient or suitable type such as a rope conveyor or small railway which passes by the said conveyor belt, and thence to wherever the bricks are to be transported. In the present embodiment I have shown the same as passing both into the dry-house and kiln-shed, and have shown the conveying belt as supplied with unburned bricks directly from a brick machine although it will be understood that this belt can equally well come from a dry-house, drying-yard, burning-shed or storage warehouse; that the bricks handled thereby can be either burned or unburned; and that they can be placed on the belt either automatically or by hand. The 30 brick machine here shown is of the stiff-mud type, comprising a suitable chamber E, from which is extruded a continuous bar of stiff clay, shown at F and conveyed by means of an endless belt G. At H this bar is severed by means of a suitable cutting device into units or bricks I each of the desired length, which are caught and carried away upon the conveying belt A which moves at a higher speed than the first belt 40 so that the bricks are separated. Furthermore, in the present embodiment I have illustrated these bricks as coming away in pairs (see Fig. 6) as is now frequently the case on such machines; although it will be understood that my invention is not limited to the type of brick machine, or to the number or arrangement of the bricks delivered thereby, or even to the origin of those bricks at a brick machine, or to their delivery by a belt conveyor, since the origin of the bricks so far as my present invention is concerned is the belt A or other conveyor upon which they are in some manner placed and from which they are to be collected.

65 The type of drying shed here shown is

wholly immaterial, and will be governed, if used at all, largely by the nature of the clay and the treatment necessary to be given thereto; it consists essentially of trestles, shelves, or other supports adapted for the reception of the pallets, suitable means being ordinarily provided to maintain such conditions of atmospheric temperature and humidity as will best conduce to the hardening of the bricks.

70 The arrangement and construction of the kilns shown at C is also independent of the present invention, although I prefer to construct and arrange them as illustrated, described, and claimed in my copending application filed March 18, 1918, Serial No. 223, 026 now Patent No. 1,305,447, and dated June 3rd, 1919. I also prefer to make them rectangular, and of a size commensurable with the pallet, but this is not imperative and can be diverged from as will hereafter be explained.

75 The conveyor D shown in Figs. 1 to 12 inclusive, comprises essentially a pair of parallel cables K—K supported on suitable rollers L—L mounted on supports or trestles M, and moving in the same direction at the same speed; the return sides of the cables being shown at N, and carried by other suitable pulleys or rollers O. At each curve 80 or bend the cables preferably pass around pulleys P—P while the pallets are received upon suitable rollers R—R, the outer rollers being larger than the inner ones, so as to bank the curve and cause the trays or pallets 85 to swing evenly therearound. These things are described merely for completeness and for convenience of reference, but no one specific structure thereof is imperative to my invention.

90 My improved pallet comprises a large, flat, rectangular tray, preferably provided with spaced transverse strips defining brick receiving channels, the length and width of the pallets being sufficient to hold the desired number of bricks. Preferably, in case the pallet is to be used in kiln building, its length is equal to the width of the body of the kiln which is to be built therefrom, in the present embodiment shown as thirty feet; while its width depends upon the width of the tramway or rope conveyor and upon the width of the passageways through which the same must pass. In the present embodiment I have chosen a width between the cables of six feet and the total width of the pallet at eight feet, thereby holding ten bricks of ordinary size arranged end to end. Said pallets preferably comprise a pair of longitudinal wood stringers 1—1 upon which are secured transverse planks 2, surmounted by the thin steel plate 3 which covers the whole device, and upon the top of which are screwed or bolted the transverse strips or cleats 4—4. These strips are spaced apart 100

105

110

115

120

125

130

a distance necessary to receive whatever number of bricks are to be delivered between them. In the present case, wherein the bricks are delivered in pairs, the same 5 are spaced in pairs, although if the bricks are delivered singly as in the case of some machines they will be spaced more narrowly, and if larger numbers are delivered together spacing will be increased. In the embodiment here shown the pallet presents seventy 10 grooves so that the load for this pallet is fourteen hundred bricks.

Where the pallet is arranged for the purpose of building a kiln, as is the case here, 15 the width of the strips is such as to afford the desired lateral spacing of the bricks in that kiln. In case the pallet is to be used for the purpose of loading or transferring or piling burned brick, wherein compact 20 arrangement is desirable, the strips are made narrower or other guiding means employed.

In some cases other guiding means can be employed, for example one or more strips not carried by the pallet. In a case where 25 the pallet is used to transport and pile previously burned brick for example, or other articles, the strips and grooves are not so important as when bricks are to be set in an accurate relation as in kiln building.

30 In order to load the pallets with brick arrayed in ranked relation, I provide means whereby the pallets as they approach the conveyor belt are inclined to such an angle as shall cause the bricks to slide gently 35 from top to bottom thereof, and also provide such mechanism that the same may be advanced in a step by step manner as the spaces or ranks become filled; after which the pallets are automatically lowered again 40 to a horizontal position and carried away in any convenient manner. In the embodiment of my invention shown in Figs. 4, 5, 45 6, 12 and 13, I effect this inclination by means of two additional cables which traverse the end of the belt A. These cables represented at 10 and 11 respectively, pass first around rollers 12-12 below and preferably between the cables K-K, and then rise gradually and uniformly above the 50 first cables, the cable 10 which is further from the belt A being elevated only a short distance by means of its rollers 13-13, and the cable 11 being elevated a much further distance by means of rollers 14-14. 55 The cables 10 and 11 are preferably so located as to engage in the angle between the stringers 1-1 and the cross members 2-2 of the pallet so as to prevent any possible side-slip.

60 While not imperative it is desirable that the advancing movement of the pallet should be so timed relatively to the movement of the conveying belt A as to occur between the arrival of successive bricks. e. One method of driving the cables and feed-

ing the pallet is illustrated in Fig. 4 wherein 15 represents the main drive shaft, to which is geared the cut-off mechanism H, (or other brick mechanism), and which also preferably drives the conveyor belt A by a 70 suitable gearing and countershafting as indicated generally at 16. The shaft 15 may, if desired, be connected to the cable K-K in driving (or driven) relation, as by the counter-shaft 17 geared to the horizontal 75 shaft 18 which carries cable-engaging pulleys indicated generally at 19.

For operating the pallet I have shown a shaft section 20, connected to suitable pulleys indicated generally at 21, 21, so as to 80 drive the same at equal speed. It will be understood that the pulleys 19 and 21 are merely indicated conventionally and that in practice a more complicated and positive arrangement is used.

I have shown an arrangement wherein a half turn of the shaft section 20 is sufficient to advance the pallet one step, and wherein this half turn occurs at a given point in the movement of the belt A. Numerous expedients can be employed for effecting this result, the simplest which has yet occurred to me being that shown in Figs. 9 and 10, wherein 25 represents a sleeve rigidly keyed to the end of the shaft 15, and loosely receiving the shaft section 20. Formed in the outer surface of the last named member is a semi-circular longitudinal groove 26 in which is rockably mounted the member 27, formed at one end with the radial finger 28. The outer surface of the member 27 is rounded so as to conform to the surface of the shaft 20, while the interior of the sleeve 25 is formed at one point with a longitudinal slot 29. A suitable spring 30 tends to rock the finger 28, but its engagement with the lever 31 pivoted in the casting 32 normally prevents such rocking. However, if at any time the lever 31 be displaced, the effect of the spring 30 is to 105 rock the member 27 into engagement with the slot 29 as soon as the rotation of the sleeve brings it into register therewith, thus locking the sleeve and extension together in driving relation. As soon, however, as the sleeve has made one revolution, the finger 28 is arrested by contact with the lever 31, thus disengaging the parts; the positions of the various parts are so chosen that the rotation referred to will occur only during the 110 interval between the delivery of successive bricks. The particular clutch here described is not a part of my invention, nor is the use of this particular device essential 115 to the performance of my invention, but I describe the same solely as being one type of operative element which may be employed in my combination.

In order to assure the discharge of the 120 bricks or other articles at the proper point 130

on the conveyor belt, I preferably provide suitable fixed guides as shown at 38. In order to prevent the bricks from sliding off the pallet at its lower end, any one of numerous means may be employed, such as an endless belt 40 carried by suitable rollers 41. No particular expedient is necessary to drive this belt, since the friction of the pallet is sufficient to effect this. This belt 10 needs to extend only from the point opposite the conveying belt A to a point where the pallet has been lowered sufficiently toward horizontal to avoid the danger of the bricks sliding off.

15 It is obvious that the approach and retreat of the pallet from the inclined position must be gradual, particularly the latter. The cables K—K being driven continuously and the cables 10 and 11 only intermittently 20 it will be seen that additional pallets will be brought up to the elevating cables with sufficient rapidity so that an empty pallet will always be at hand to render the operation continuous. Similarly, as soon as the filled 25 pallets are delivered from the elevating cables on to the conveying cables, they will be moved away rapidly and uniformly to the point of use.

Assuming the clay to be of such nature 30 that the bricks can be put into kilns immediately upon pressing, the pallet is conveyed directly to the kiln shed, where it is caught up by a traveling crane, transported to the kiln which is being built, spotted to 35 the exact position desired, inclined from side to side to an amount necessary to cause the bricks to slide, and then drawn slowly backwardly so that the bricks may be discharged therefrom as shown in Fig. 2. The inter- 40 action of the bricks caused by their length and height causes them to be deposited in longitudinally separated relation as shown in Fig. 2, so that no hand-work whatever is required to be done thereon; while the cross- 45 wise arrangement of alternate layers or courses is provided by applying the pallets to the kiln first in the one direction and then in a direction transverse thereto. This last can easily be done, either by providing 50 the crane with a turn-table whereby the pallets can be rotated in mid-air, or by picking up the pallets on one or the other side of a right angle turn made by the transporting device.

55 The crane shown is of the usual rectilinear type, comprising a rectangular frame 50 running by means of wheels 51—51 upon a pair of longitudinal rails 52—52 and itself carrying a transversely movable platform 53, having wheels 54 running upon the side members of the frame. Mounted upon the carriage 53 is the turn-table 55, operated by a motor 56; and carried by the turn-table are a pair of hoisting drums, 57 and 58, the 60 former of which is connected by a fall 59 to

the balancing point of the carrier 60, and the latter of which is connected by a fall 61 with the rearward part of the carrier. The carrier consists of a rigid frame having a plurality of parallel horizontal arms 62 70 adapted to receive one of the pallets thereon, said frame being connected to the falls in such manner that any desired inclination can be imparted to the pallets. To discharge a pallet, the crane is spotted over the exact 75 point that it is desired to deposit the bricks after which the fall 59 is lowered and the fall 61 raised so as to elevate the rearward end of the carrier to a degree sufficient to cause the bricks to slip; thereupon the crane 80 is set in motion so as to withdraw the pallet from beneath the bricks which are thereby deposited smoothly, easily, and in correct position as shown in Fig. 2.

The first brick of each rank is preferably 85 located in its desired place by means of a suitable stop such as the plank 65, which may be held by workmen until the deposition of the bricks has started. The casing or outer wall of the kiln is built up by hand 90 after the middle part has been laid. Any number of bricks less than the whole capacity of the pallet can be laid at one time if desired. It is merely necessary, when the desired number have been set down, to elevate the cable 59 and lower the cable 61; similarly, it is possible to lay a small number in the opposite direction if desired, either by filling only part of the spaces on 95 the pallet or by holding certain ranks of 100 bricks against discharge therefrom. It is easy in this way to build any sort of irregular structure which may be required, such as to lay the lower part of the kiln where the arches are located, or to deposit bricks around the exterior of the kiln to be built by hand into the outer wall thereof as heretofore explained, or load a wagon, car, or boat. The conveyor D is preferably 105 formed with a right angle curve at at least 110 one point within the range of the crane movement, as shown at 70, so that by taking up a pallet at one or the other side of the curve the proper orientation of the bricks 115 is secured without the necessity of turning the pallet in mid-air.

In case a drying house is used the arrangement differs in no way from that heretofore described. At B in these drawings I have shown a suitable dry house comprising longitudinal racks 71 and transverse racks 72, each consisting of a plurality of vertically spaced brackets adapted to receive the pallets and hold them while the bricks thereon are drying. The conveying device 120 preferably makes a right angle turn inside or at least near this drying house for the same reason as in the kiln, namely to permit pallets to be picked up in either position, and transferred to the correspondingly 125 130

oriented brackets. In the present embodiment the dry-house and the kiln-shed are arranged close together so that the same crane can transfer the pallets from the conveyor D either to the brackets or to the kiln, or from the brackets to the kiln. My improved pallet is much cheaper to construct, longer in life, and more easily handled than the dry cars now ordinarily used, whereof it

10 is entirely practical to use it in this manner.

In Fig. 13 I have shown a modified arrangement for conveying the said pallets which in some ways is simpler than that heretofore illustrated although dependent upon the same identical principle. In this embodiment the pallet, indicated generally at 2, is carried upon the top 75 of a suitable truck having car wheels 76 running upon rails 77. The pallets are raised to their inclined position (shown in the dotted lines) by means of rollers 78 spaced in the same way as the rollers 14 shown in Figs. 5 and 6, the opposite side of the car being provided with a wall or side 79 adapted to prevent the overshooting of the bricks. The step by step movement of the car during loading is effected in any suitable way, such as by means of a rack 80 meshing with a suitable pinion 80^a which takes the place of the rollers 21, 21 shown in Fig. 4. At other times these cars are propelled along their track in any manner such as by a cable 81 connected to the car by grips in such wise, for example, that it will be relieved either when the pallet 2 is elevated, or when the car comes into contact with the car ahead. This is easily effected by having one side of the grip, as 82, pivoted on a horizontal axis and provided with an arm 83 adapted to be depressed when the pallet rests thereon but to release the cable when the same is raised either by the roller 78 or by the crane. The other side of the grip, as 84, is pivoted upon a vertical axis and connected to a bumper 85 so as to release the cable when the car comes into contact with the car ahead.

The belt A may derive its bricks either from a brick machine or from any other source, and the same may be either burned or unburned, and placed thereon either manually or automatically. The pallets may be filled either by the means and method here shown or in any other way, for example manually; for in many cases it would be highly advantageous to employ such a pallet solely for the facility in transporting and discharging the bricks in the desired relation, even though placed thereon by hand. The pallets may be used either for building kilns, or for setting other structures, for piling burned bricks on conveyances or in storage, or they may be used solely for drying purposes. The various embodiments of the invention herein shown have been selected and described as illustrative only and not as

limiting in any degree. Wherefore it will be clear that the use and performance of my invention and the mechanical means employed can be varied very widely without departing from my inventive idea, which is limited only by the prior art and by the terms of the annexed claims.

Having thus described my invention, what I claim is:—

1. In a device of the character described, the combination with a conveying belt, of transporting mechanism extending past said belt, trays or pallets carried by said mechanism and movable thereby in a direction parallel to the plane of said belt, and means for inclining said pallets during the period of their passage by said belt, whereby they may become filled with the articles delivered by said belt. 75

2. The combination with a conveying belt, of transporting mechanism traversing said belt, pallets carried by said mechanism, means for inclining each pallet during the period of its passage by said belt, whereby it may become filled with the articles delivered by said belt, and means movable with said pallet upon the opposite side thereof from said belt for preventing the overrunning of said articles. 80

3. In a device of the character described, the combination with a conveying belt, of transporting mechanism extending past said belt, trays or pallets carried by said mechanism, means for inclining said pallets during their passage by said belt and presenting their edges to such belt so as to receive and become filled with the articles delivered thereby, and means thereafter restoring said pallets to horizontal position. 95

4. The combination with a conveying belt, of transporting mechanism traversing said belt, pallets carried by said mechanism and movable thereby in a direction parallel to the plane of said belt, means for removing said pallets from said transporting mechanism upon their arrival near said belt and for inclining them in a direction away from said belt, means for presenting the inclined pallets to said belt so as to receive the articles delivered thereby, and means for thereafter restoring said pallets to a substantially horizontal position and delivering them to said transporting mechanism. 100

5. In a device of the character described, the combination with a conveying belt, of transporting mechanism extending past said belt, trays or pallets carried by said mechanism, means for inclining said pallet as it approaches said belt, means for restoring said pallet to an approximately horizontal position after passing said belt, and means for advancing said pallet in step by step manner during its passage past said belt, whereby it may receive articles therefrom in ordered ranks. 115

6. In a device of the character described, the combination with a conveying belt, of transporting mechanism extending past said belt, trays or pallets carried by said mechanism, means for inclining said pallets during their passage by said belt and presenting their edges to such belt, means for advancing said pallet in step by step manner during its passage past said belt so as to become filled with the articles transported thereby, and means for causing the advancing movement to said pallet to take place during the interval between the arrival of successive articles upon said belt.
- 15 7. In a device of the character described, the combination with a conveying belt, of means opposite the end of said belt for supporting a pallet, a pallet on said supporting means, and mechanism for advancing said pallet in step by step manner whereby it may be filled with orderly ranks of articles delivered by said belt.
8. In a device of the character described, the combination with a conveying belt, of means opposite the end of said belt for supporting a pallet in inclined position, a pallet on said means and inclined away from said belt, the upper edge of said pallet being presented to said belt in receiving relation, and means for advancing said pallet past said belt in a step by step manner.
9. The combination with a conveying belt for articles of a carrying device having parallel grooves of a width to receive such articles, means for supporting said device with its edge in receiving position relatively to the said belt and its grooved portion inclined away from said edge, means for guiding the articles delivered by said belt, and means for advancing said device intermittently by steps commensurable with the distance between adjacent grooves and for stopping the same so that said grooves will register with the articles delivered.
- 45 10. In brick machinery, the combination with means for delivering brick successively, of a pallet-transporting device traversing said means, pallets on said device, means for inclining each pallet during its passage by said first means to an angle such that the bricks will slide gently upon the surface thereof, means for advancing the pallets in a step by step manner while so inclined, and means for guiding the bricks in their motion across said pallet.
11. In brick machinery, the combination with a conveying device for bricks, of a pallet, a pallet-transporting device adjacent to said device, means for inclining said pallet during its passage by said device to an angle such that the bricks will slide gently upon the surface thereof, means for advancing the pallet in a step by step manner while so inclined, means for guiding the bricks in their motion across said pallet,

and means separate from said pallet but movable therewith at its lower edge for preventing the overrunning of said bricks.

12. In brick machinery, the combination with a conveying device for bricks, of a pallet-support traversing said device, and arranged to support a pallet in position inclined away from said device but having its upper edge in receiving relation relatively to said device, means for advancing the pallets, means for guiding said bricks upon said device, and means in alignment with said first means for guiding said bricks in their movement across the pallets.

13. In brick machinery, the combination with a conveying device for bricks, of a pallet-support traversing said device, and arranged to support a pallet in a position inclined away from said device but having its upper edge in receiving relation relatively to said device, means for advancing the pallets, means for guiding said bricks upon said device and across the said pallets, and means upon the opposite side of said pallets for preventing the overrunning of the bricks.

14. In brick handling apparatus, the combination with a carrying device having a plurality of spaced brick-receiving channels, each channel having a bottom portion upon which the bricks can rest and be supported, of a conveying belt for bricks, means for moving said carrying device laterally past the belt in an intermittent manner whereby said channels may become filled with bricks in ranked relation, and means for thereafter removing said carrying device from said belt by continuous movement.

15. In brick handling apparatus, the combination with transporting mechanism whereby pallets can be moved from point to point in horizontal position, a conveying device for bricks, means for transferring said bricks from said device to said pallet in ranked relation, means for thereafter removing said pallet bodily from said transporting means, and means for thereafter inclining said pallet and moving it horizontally whereby the bricks can be discharged therefrom in orderly relation.

16. In brick handling apparatus, the combination with transporting mechanism whereby pallets can be moved from point to point in horizontal position, a conveying device for bricks, and means for presenting such pallets to said device in inclined position to receive said bricks from said device in ranked relation, means for restoring said pallets to horizontal position and for transporting them elsewhere, and means for inclining said pallets and simultaneously moving them laterally so as to discharge the bricks therefrom.

17. In brick handling apparatus, the com-

combination with a carrying device, of means for transporting that device from point to point in a substantially horizontal position, a conveying device adapted and arranged 5 for delivery of bricks in succession, means for presenting said carrying device to said conveying device so as to receive in ranked formation the bricks delivered thereby, means for thereafter removing said carrying device bodily from said transporting means together with the bricks thereon, and means for thereafter discharging the bricks from said carrying device simultaneously in 10 a predetermined piled relation.

15 18. In brick handling machinery, in combination, a conveying device for delivering bricks successively, a pallet, a pallet-trans- porting means traversing said device and arranged normally to convey said pallet in

substantially horizontal position, means op- 20 erative upon the approach of said pallet to said device for inclining the same and presenting the same to said device in such manner that the bricks delivered from the device will slide upon and across said pallet, 25 means for advancing said pallet in step by step manner during its presentation to said device, means located at the further side of said pallet for preventing the overrunning of the bricks, means operative after the pallet has passed by said device for restoring 30 the same to its horizontal position, and means for thereafter removing said pallet bodily from the transporting means with 35 all the bricks thereon.

In testimony whereof, I hereunto affix my signature.

WILLIAM WALLACE DICKINSON, Jr.
